Patented Oct. 23, 1917.

FIG. 1.

FIG. 2.

FIG. 3.

FIG. 4.

INVENTOR:
August Lindstrom
BY his ATTORNEY,
A.M. Carlsen.

UNITED STATES PATENT OFFICE.

AUGUST LINDSTROM, OF CENTERVILLE, SOUTH DAKOTA.

HARNESS-LINE HOLDER.

1,244,350.

Specification of Letters Patent. Patented Oct. 23, 1917.

Application filed February 26, 1917. Serial No. 150,897.

To all whom it may concern:

Be it known that I, AUGUST LINDSTROM, a citizen of the United States, residing at Centerville, in the county of Turner and 5 State of South Dakota, have invented a new and useful Harness-Line Holder, of which the following is a specification.

My invention relates to improvements in harness for horses and other draft animals, 10 and the main object is to provide the back pad of a harness with a handy device for holding the lines of the harness when they are not in use. Another object is to make such device readily applicable as an attachment also to harness already manufactured 15 or even in use.

In the accompanying drawing:

Figure 1 is a rear elevation of a back-pad with my line holder mounted on it. Fig. 20 Fig. 2 is a top view of Fig. 1. Fig. 3 is an enlarged and slightly modified portion of Fig. 1 with the regular metallic parts of the back pad partly in section. Fig. 4 is a view in the direction of the arrows A in Figs. 2 and 25 3, of the attachment only.

Referring to the drawing by reference numerals, 1 designates an ordinary back pad, having certain metallic parts, 2, secured in place on it by screws 3, 4, having nuts 30 3^A, 4^A, in the pad proper. Other metal parts are the plates 5, on each of which is mounted a terret 6 having a threaded shank, 7, extending downward through the plate and screwed into a nut 8, fixed in the pad. Each 35 terret plate 5 is provided near its lower end with a downward stud 9 adapted to engage in apertures in the belly bands 10 and shaft supporting straps 11, through which are also passed the screws 4 that extend down 40 through apertures in bridge bars 12. The upper end of each terret plate is formed into a hinge member 13, which engages a hinge member 14, of the metal arch 15, on which the check rein hook 16 is secured. The plate 45 5 is also formed with a bayonet point 17, which is passed down through apertures 18, 19 in the parts 15 and 2 respectively, (see Fig. 3) and under part 2, whereupon the plate 5 is further secured by the terret 6 50 and the nut 8.

From this description it will be seen that the terret plate 5 is detachable by merely removing the terret and raising the plate with its lower end until the bayonet end 17 55 will be disengaged and removed from the other parts. Of this detachable character

of the terret plate I take advantage by mounting upon said plate 5 my line holder, which will now be described.

Referring to Fig. 3 where the terret is 60 preferably of the quadrangular type to give more room for the line holder, the latter consists of a curved plate or bracket 20, cast integral with the plate 5, and having a large aperture 21 and near its base two lugs 22, 65 supporting a pivot 23, on which is mounted a finger lever 24, having an upward arm 25, with a flat finger 26 at its upper end. Said arm is normally impelled toward the bracket 20, by a spring 27 having a loop-shaped arm 70 28 pressing upon the lever 24. In this way the device requires a new terret plate to be cast with it and applied to new harness, or the plate may be exchanged for the common terret plate of a harness already manufactured or in use. 75

In either of such cases the plate 5 may or may not have the extension 5^x shown in Figs. 3 and 4, for the screw 4. But where the line holder is secured upon an old or 80 existing common plate 5, the perforated extension 5^x becomes necessary or at least very desirable and then forms a part of a special plate 29.

The latter form is shown in Figs. 1 and 85 2, where the bracket 20 is formed with a special foot or base 29, which is set upon the plate 5 and may be secured thereto by a rivet 30 and be drawn down tight by the screw 4, upon interposed leather washers 31 90 to support it upon the leather straps 11 and 10. The bracket proper may also be secured to the terret by solder 32 or by having a flat finger 33 inserted through a slit made in the terret, and then clenched within the 95 terret, as indicated by 33, in Fig. 1. The foot plate 29 may also have a notch 29^x (in Fig. 1) fitting the adjacent side of the collar 6^x of the terret. In either form of the device I prefer to arrange the bracket in a 100 more or less oblique position relative to the transverse direction of the back pad upon the horse. This to give better access to the use and operation of the device, which use is simply as follows:

For a single harness the device is usually placed upon the left side of the harness as shown, and for a double harness, the right side of the right hand harness is provided with a similar device, only so much different 110 from the one shown that when it is put in place the bracket 20 must be inclined for

wardly with its outer edge about as indicated by the line *b*—*b* in Fig. 2, and have its concaved side rearwardly. It will thus require reversely shaped patterns for the 5 right and left brackets but the spring and the lever 24 and arms 25 are the same form for both sides.

When the horse or horses are unhitched for rest or to be fed, or whenever it is desired to set the driving lines free from 10 the vehicle, they are simply doubled up in a few coils so they cannot reach the ground and are placed in the clasp formed by the bracket 20 and the arm 25 as a pair of jaws. When the reins are to be inserted 15 or removed, said jaws are temporarily forced open by one of the operator's hands, placed with the palm upon the top of the bracket and engaging with the fingers over 20 the top of the lever 24 to close it toward the bracket until the lines are put in place by the other hand, whereupon the lever is released so the spring 27—28 can act and close the arm 25 until its finger 26 may 25 reach the bracket and the lines are firmly gripped between the arm and the grooved or concaved and perforated bracket.

If there is a hitching strap or other strap to be supported, the same may also be placed 30 in the clasp either above the lines or better below them so that if the horse starts to walk away the lines may in an instant be removed from the clasp and ready for service. The advantages of this device can be readily 35 understood when compared to earlier devices, the use of which requires the idle reins to be supported by coiling and inserting them into the terret and sometimes even tying them thereto so they may not slip 40 accidentally away from the terret or from some other part of the harness to which they are also sometimes tied.

What I claim is:

1. The combination with a plate, of a 45 spring-closed clasp mounted on said plate for holding lines, reins and the like parts of the harness in idle position; said clasp comprising an upstanding bracket with an aperture in it and lugs at its base, a pivot 50 in the lugs, a lever mounted to swing on the

pivot and having two arms, one of which is arranged to clamp the lines against the adjacent side of the bracket, the other one extending through the aperture in the bracket and serving as a finger catch for 55 operating the arm, and a spring acting on the lever to close the arm against the bracket; said spring being mounted on the pivot, between the supporting lugs and the said lever.

2. The combination with a plate, of a 60 spring-closed clasp mounted on said plate for holding lines, reins and the like parts of the harness in idle position; said clasp comprising an upstanding bracket with an 65 aperture in it and lugs at its base, a pivot in the lugs, a lever mounted to swing on the pivot and having two arms, one of which is arranged to clamp the lines against the adjacent side of the bracket, the other one 70 extending through the aperture in the bracket and serving as a finger catch for operating the arm, and a spring acting on the lever to close the arm against the bracket; said bracket having its body 75 grooved at the side adjacent to the spring-closed arm.

3. The combination with a plate adapted 80 to be attached to a back pad, of a spring-closed clasp mounted on said plate for holding lines, reins and the like parts of the harness in idle position, said clasp comprising an upstanding bracket with an aperture 85 in it and lugs at its base, a pivot in the lugs, a lever mounted to swing on the pivot and having two arms, one of which is arranged to clamp the lines against the adjacent side of the bracket, the other one extending through the aperture in the bracket and serving as a finger catch for 90 operating the arm, and a spring acting on the lever to close the arm against the bracket, the body of said bracket being of approximately flat form and arranged on the said pad with its outer edge farther forward than the inner 95 edge, to make it more convenient to operate and use the device.

In testimony whereof I affix my signature.

AUGUST LINDSTROM.
